UNITED STATES PATENT OFFICE.

RICHARD F. FITZHENRY AND JOHN G. EBNER, OF CHICAGO, ILLINOIS.

FREIGHT-ROUTING APPARATUS.

1,188,060.

Specification of Letters Patent. Patented June 20, 1916.

Application filed June 25, 1915. Serial No. 36,300.

To all whom it may concern:

Be it known that we, RICHARD F. FITZHENRY and JOHN G. EBNER, citizens of the United States, and residents of the city of Chicago, county of Cook, and State of Illinois, have invented certain new and useful Improvements in Freight-Routing Apparatus, of which the following is a specification.

10 Our invention relates to improvements in freight routing systems and has for its object the production of a system of this character through the medium of which the possibility of the misplacing of freight in 15 freight cars will be practically obviated.

A further object is the production of a system as mentioned involving apparatus which will be of economical construction and efficient in use.

20 Other objects will appear hereinafter.

The invention consists in the combinations and arrangements of parts hereinafter described and claimed.

The invention will be best understood by 25 reference to the accompanying drawings, forming a part of this specification, and in which,

Figure 1 is a front elevation of one of the devices used in connection with the system, 30 Fig. 2 is a top plan view of Fig. 1, Fig. 3 is a section taken on substantially line $x-x$ of Fig. 1, and Fig. 4 is an enlarged detail section taken on line $y-y$ of Fig. 2.

The preferred form of construction as 35 illustrated in the drawings comprises a rectangular sheet metal box or casing 1 open at its front side and provided with a transversely extending partition 2 which divides the interior of said box into compartments 40 3 and 4. In the latter compartment is provided an electric battery 5. Formed in the upper wall of compartment 3 adjacent the rearward edge thereof is a plurality of spaced perforations 7 and correspondingly 45 formed in the partition 2 are spaced perforations 8, said perforations being adapted for engagement by loosely mounted vertically extending rods 9. At the upper ends of rods 9 are provided enlargements or col- 50 lars 10 which are adapted to engage against the upper side of wall 6 to limit downward sliding of said rods. The perforations 7 are designated by digits A, there being three sets of said characters, the first of which 55 includes digits from 1 to 9 inclusive, the

other two each including digits from 1 to 0 inclusive.

A box is intended to be mounted in each freight car to be loaded, each box having a number indicated at B provided upon the 60 front side of the upwardly extending portion of the rear wall thereof which corresponds with the spot occupied by the car, that is the location of the car in the freight yard, said spot being used also to indicate 65 a certain destination. In the present case the box and the spot are numbered 137. The rods 9 are arranged to correspond with this number, the first digit and number or 1 being represented by the left hand rod 9 70 occupying the corresponding perforation in connection with the first set of characters A. The second and third digits of said number are represented by the other two rods 9 occupying corresponding positions 75 in connection with the other two sets of characters A as clearly shown in Fig. 2.

In connection with the box are employed cards or tickets 11, a card being employed 80 in connection with each shipment which is to be loaded in the freight cars. Each card is provided at its front side with transversely extending lines or graduations C, the spaces between said lines at one edge of the card being designated by characters 85 D corresponding as will be seen with the characters A. As the shipments come into the freight house, the routing clerk determines the route for the shipment and places the corresponding number opposite the spot 90 indicated upon the card as shown at E. Then by means of a punch he indicates this number by punching along the graduated edge of the card forming slots 12. As each shipment reaches the car and is loaded in 95 the same, the card accompanying the shipment is required to be placed in the corresponding box 1. It will be seen that if the shipment is in the proper car the slots 12 in the card will register with the rods 9 of 100 the box so as to permit of complete insertion of the card. If the shipment is not in the proper car it will be seen that the slots in the card will not register with the rods 9 thus preventing the complete insertion of 105 the card. This, of course, will serve to advise the loader that the shipment is in the wrong car. To further advise the loader in case of error the front side of the box is provided with guide rods 13 upon which is 110

slidably mounted a cross bar consisting of two sections 14 and 14' which are connected at their inner ends by a block 15 of insulating material. Mounted in the block 15, as clearly shown in Fig. 4, is a vertically movable T-shaped member 16 adapted, when in normal position or at its lower terminal of movement, to be positioned out of engagement with the adjacent ends of members 14 and 14'. In case of a card projecting from the box as when a wrong card is inserted in the box, the edge of the same will protrude into the path of the member 16 so that when the cross bar is slid downwardly the lower end of the member 16 will contact with the upper edge of the card and will be moved upwardly into engagement with the ends of members 14 and 14' and thereby electrically connect the same. An electric bell 17 is provided upon one side of the box, one terminal of which is connected by a wire 18 with one of the guide rods 13, the other terminal of the bell being connected by a wire 19 with one pole of the battery 5. The other pole of the battery is connected by a wire 20 with the other guide rod 13. By this arrangement it will be seen that the circuit through the bell and battery is broken at the insulating block 23 so that upon elevation of the member 16 as just mentioned the circuit through the bell will be closed and thus cause the same to be sounded. The freight loader in inserting a card into the box will be required to first raise the cross bar 14—14', so that when the cross bar is released and moved downwardly by gravity, in the case of a card protruding from the box the member 16 will be elevated and thus the bell 17 automatically sounded to audibly advise the loader that a mistake has been made. To facilitate vertical movement of the cross bar a forwardly projecting handle 21 is provided upon the cross bar which may be readily and easily engaged in the movement of the latter. Upon the cross bar is also provided an inwardly projecting finger 22 which is adapted to engage against the upper sides of the cards to hold the same in place. This finger will also serve to indicate whether or not the cross bar was elevated before the insertion of a card, it being clear that in the event of a card having been inserted without first having raised the cross bar the finger 22 will be positioned below instead of above the card.

With a system as above described it is believed that it will be practically impossible to load freight shipments in a wrong car, the check upon the placing of the freight with this system, being so thorough as to practically eliminate error.

While we have illustrated and described the preferred form of construction for carrying our invention into effect, this is capa-

ble of variation and modification without departing from the spirit of the invention. We, therefore, do not wish to be limited to the precise details of construction set forth, but desire to avail ourselves of such variations and modifications as come within the scope of the appended claims. 70

Having described our invention what we claim as new and desire to secure by Letters Patent is:

1. In a freight routing system, the combination of a plurality of tickets each bearing a series of graduations along one edge adapted to serve as a guide in the slotting of said edge; a receptacle adapted to snugly receive said tickets; obstructions disposed perpendicularly relative to said tickets when arranged in said receptacle adapted for registration with and reception in the slots in said tickets; and means whereby the positions of said obstructions in said receptacle may be adjusted in a direction longitudinally of the slotted edges of said tickets, said positions and the graduations upon said tickets being correspondingly designated, 80 substantially as described. 85

2. In a freight routing system, the combination of a plurality of tickets each bearing a series of graduations along one edge adapted to serve as a guide in the slotting of said edge; a receptacle adapted to snugly receive said tickets; obstructions disposed perpendicularly relative to said tickets when arranged in said receptacle adapted for registration with and reception in the slots in 95 said tickets; means whereby the positions of said obstructions in said receptacle may be adjusted in a direction longitudinally of the slotted edges of the tickets; and a plurality of series of digits correspondingly 100 designating said positions and the graduations upon said tickets, substantially as described. 105

3. In a freight routing system, the combination of a plurality of tickets each bearing a series of graduations along one edge adapted to serve as a guide in the slotting of said edge; a receptacle adapted to snugly receive said tickets; obstructions disposed perpendicularly relative to said tickets when arranged in said receptacle adapted for registration with and reception in the slots in 110 said tickets; means whereby the positions of said obstructions in said receptacle may be adjusted in a direction longitudinally of the slotted edges of the tickets; a plurality of series of digits correspondingly designating said positions and the graduations upon said tickets; and a number applied to the receptacle corresponding with the number 115 represented by the positions of said obstructions, substantially as described. 120

4. In a freight routing system, the combination of a plurality of tickets each bearing a series of graduations along one edge adapt- 125

ed to serve as a guide in the slotting of said edge; a receptacle adapted to snugly receive said tickets; obstructions disposed perpendicularly relative to said tickets when arranged in said receptacle adapted for registration with and reception in the slots in said tickets; characters correspondingly designating the positions of said obstructions and the graduations upon said tickets; and a designation upon said receptacle corresponding with the characters represented by the positions of said obstructions, substantially as described.

and reception in the slots in said tickets and adapted to prevent complete insertion into said receptacle of a ticket not slotted to correspond with said obstruction; an alarm mechanism; and a cross bar mounted for movement adjacent the mouth of said receptacle and in a direction transversely of the plane of the tickets positioned in said receptacle, said bar being adapted for engagement with a ticket not completely inserted into said receptacle to effect actuation of said alarm mechanism, substantially as described.

5. In a freight routing system, the combination of a plurality of tickets each bearing a slot in one edge; a receptacle for the reception of said tickets; an obstruction in said receptacle adapted for registration with and reception in the slots in said tickets and adapted to prevent complete insertion into said receptacle of a ticket not slotted to correspond with said obstruction; an alarm mechanism; and means whereby said alarm mechanism will be actuated through the medium of a ticket not completely inserted into said receptacle, substantially as described. 15 20 25

9. In a freight routing system, the combination of a plurality of tickets each bearing a slot in one edge; a receptacle for the reception of said tickets; an obstruction in said receptacle adapted for registration with and reception in the slots in said tickets and adapted to prevent complete insertion into said receptacle of a ticket not slotted to correspond with said obstruction; an alarm mechanism; a normally open electric circuit adapted when closed to effect actuation of said alarm mechanism; means whereby said circuit will be closed through the medium 80 85 90

6. In a freight routing system, the combination of a plurality of tickets each bearing a slot in one edge; a receptacle for the reception of said tickets; an obstruction in said receptacle adapted for registration with and reception in the slots in said tickets and adapted to prevent complete insertion into said receptacle of a ticket not slotted 95
30 to correspond with said obstruction; an alarm mechanism; a normally open electric circuit adapted when closed to effect actuation of said alarm mechanism; and means whereby said circuit will be closed through 100
35 the medium of a ticket not completely inserted into said receptacle, substantially as described. 105
40

7. In a freight routing system, the combination of a plurality of tickets each bearing a slot in one edge; a receptacle for the reception of said tickets; an obstruction in said receptacle adapted for registration with and reception in the slots in said tickets and adapted to prevent complete insertion into said receptacle of a ticket not slotted to correspond with said obstruction; an alarm mechanism; and a member mounted for movement adjacent the mouth of said receptacle and in a direction transversely of the plane of the tickets positioned in said receptacle, said member being adapted for engagement with a ticket not completely inserted into said receptacle to effect actuation of said alarm mechanism, substantially as described.

8. In a freight routing system, the combination of a plurality of tickets each bearing a slot in one edge; a receptacle for the reception of said tickets; an obstruction in said receptacle adapted for registration with receptacle, substantially as described.

said receptacle adapted for registration with and reception in the slots in said tickets and adapted to prevent complete insertion into said receptacle of a ticket not slotted to correspond with said obstruction; an alarm mechanism; a member mounted for movement adjacent the mouth of said receptacle and in a direction transversely of the plane of the tickets positioned in said receptacle, 10 said member being adapted for engagement with a ticket not completely inserted into said receptacle to effect actuation of said alarm mechanism; and a finger on said member projecting inwardly into the receptacle for engagement with the tickets positioned therein, substantially as described.

12. In a freight routing system, the combination of a plurality of tickets each bearing a slot in one edge; a receptacle for the reception of said tickets; an obstruction in said receptacle adapted for registration with and reception in the slots in said tickets and adapted to prevent complete insertion into said receptacle of a ticket not slotted to correspond with said obstruction; an alarm 20

25

mechanism; a normally open electric circuit adapted when closed to effect actuation of said alarm mechanism; means whereby said circuit will be closed through the medium of a ticket not completely inserted into said receptacle, said means comprising a member included in said circuit mounted for movement adjacent the mouth of said receptacle and in a direction transversely of the plane of the tickets positioned in said receptacle; 30 switch mechanism carried by said member adapted to be closed through contact with a ticket not completely inserted into said receptacle; and a finger on said member projecting inwardly into the receptacle for engagement with the tickets positioned therein, 35 substantially as described.

In testimony whereof we have signed our names to this specification in the presence of two subscribing witnesses.
